UNITED STATES PATENT OFFICE.

LAURENCE N. FLAMINI, OF SOUTH BETHLEHEM, PENNSYLVANIA.

PIPE.

1,181,865.

Specification of Letters Patent.

Patented May 2, 1916.

Application filed September 8, 1915. Serial No. 49,532.

To all whom it may concern:

Be it known that I, LAURENCE N. FLAMINI, a subject of the King of Italy, residing at South Bethlehem, in the county of Northampton and State of Pennsylvania, have invented certain new and useful Improvements in Pipes, of which the following is a specification:

This invention relates to a smoking pipe and the principal object of the invention is to provide a device for connecting the bowl with the stem of the pipe, the connecting element being so constructed as to prevent nicotine from passing from the bowl of the pipe with the smoke into the mouth of the smoker.

Another object of the invention is to provide the connection for the bowl and stem with means for causing the smoke to travel in a spiral course, the threads for accomplishing this object also forming means for removing any nicotine from the stem when the connection is removed completely.

Another object of the invention is to so construct the bowl and connection that a saliva pocket will be formed thus preventing saliva from entering the bowl and causing the bowl to be soggy.

This invention is illustrated in the accompanying drawings, wherein:—

Figure 1 is a view showing the improved pipe in longitudinal section, and Fig. 2 is a view showing the connection in elevation.

The bowl 10 is provided with the neck 11 having a smoke passage 12 communicating with the lower end of the tobacco chamber 13 of the bowl. This smoke passage 12 leads from the saliva chamber 14 which chamber is at the inner end of the internally threaded socket 15. A reinforcing collar 16 is provided so that the neck of the bowl will be prevented from cracking when the connecting device is screwed into the socket. It should be noted that the saliva pocket 14 is of less diameter than the threaded socket 15 thus providing an abutment shoulder 17 to limit the inward movement of the connection.

The stem 18 is provided with a smoke passage 19 which leads from the chamber 20 which chamber has its outer end portion 21 threaded for engagement with the threaded head 22 of the connection 23. This connection 23 is provided with threads 24 which form baffles so that the smoke when passing around the connection in the pocket 20 will

travel in a spiral course and thus the nicotine which passes through the smoke passage 25 will be removed from the smoke and deposited in the chamber 20 upon the walls 26 thereof and upon the connection 23 in the spiral smoke passage.

When assembling this pipe the connection is thrust into the pocket 20 and its threaded head 22 is then screwed tightly into the threaded outer end portion 21 of the pocket 20. The neck 11 of the bowl is then screwed upon the head 22 of the connection and the pipe is ready for use. It should be noted that the construction shown in Figs. 1 and 2 the smoke passages 12 and 25 are of the same diameter so that the saliva may gather in the pocket 14 without interrupting the passage of smoke through the same. When it is desired to clean the pipe the bowl will be removed and the connection then disengaged and drawn outwardly. This will cause the threads 24 to scrape along the walls of the pocket 20 thus removing any nicotine and saliva which may gather upon the walls of the pocket. After the connection has been removed it may be wiped clean with a cloth or brush and the smoke passages 25 and 12 cleaned with an ordinary pipe cleaner. The saliva which may have gathered in the pocket 14 can then be removed and the pocket wiped dry and the smoke passage 12 cleaned with the ordinary pipe cleaner. The pipe can then be reassembled and will be ready for use.

It will thus be seen that I have provided a pipe which can be easily cleaned and which is constructed so that nicotine will be prevented from entering the mouth of the smoker and further that the connection is so constructed that it not only provides means for connecting the stem with the bowl of the pipe but serves as means for cleaning the pocket 20. It should also be noted that by providing this structure the smoke is cooled and will therefore not bite the tongue but will provide a cool smoke.

What is claimed is:—

A pipe, comprising a bowl having a neck provided with a smoke passage, a threaded pocket arranged within said neck and communicating with said smoke passage, said pocket having its inner end reduced to provide a saliva pocket and an annular shoulder, a single piece stem associated with the bowl, a portion of the stem being internally threaded adjacent its outer end, a

connection for securing the stem to said bowl, comprising a solid cylindrical member having an enlarged externally threaded portion adjacent one extremity, said externally threaded portion adapted for engagement with the internally threaded pocket and to abut said annular shoulder, a spiral smoke passage arranged about a portion of said connection, and a smoke passage ex-

tending longitudinally through the enlarged 10 portion of said connection communicating with the spiral passage.

In testimony whereof I affix my signature in presence of two witnesses.

LAURENCE N. FLAMINI.
